UNITED STATES PATENT OFFICE.

EDWIN B. STIMPSON, OF BROOKLYN, NEW YORK.

DESIGN FOR THE ORNAMENTATION OF STRAPS.

SPECIFICATION forming part of Design No. 18,928, dated February 12, 1889.

Application filed January 3, 1889. Serial No. 295,352. Term of patent 7 years.

To all whom it may concern:

Be it known that I, EDWIN B. STIMPSON, of Brooklyn, in the county of Kings and State of New York, have invented and produced a new and original Design for Ornamenting Straps, of which the following is a specification.

I will describe my design for ornamenting straps in detail, and then point out the novel features in a claim.

- The accompanying drawing illustrates on a large scale my design for ornamenting straps. The design consists of a band having one of its side edges made up of series of angles *a*, forming together a continuous zigzag line, *A*.
- 5 The other edge of the band is composed substantially of a series of curved lines, *b*, and enlarged substantially dot-like portions *c*. In-

termidate of the curved lines *b*, between the angles *a* of the zigzag line and the dot-like portions *c*, extend zigzag or angular lines *d*. 20

What I claim as my design is—

A design for the surface ornamentation of a strap, consisting of a band having the zigzag line *A* upon one of its edges, and its other edge composed of the curved portions *b* and 25 enlarged dot-like portions *c*, and zigzag lines *d*, intermediate of the zigzag line *A* and the lines *b* and dot portions *c*, substantially as shown and described.

EDWIN B. STIMPSON.
